UNITED STATES PATENT OFFICE

GEORGE E. LITTLEFIELD, OF PROVIDENCE, RHODE ISLAND, ASSIGNOR TO AMERICAN ROLL GOLD LEAF COMPANY, A CORPORATION OF RHODE ISLAND

TOOL FOR DELIVERING, SEPARATING, AND APPLYING ROLL GOLD LEAF

Application filed July 10, 1929. Serial No. 377,102.

My invention relates to hand tools for delivering the fillet or ribbon of metallic leaf from the supporting strip with which it is packaged in roll form, depositing a length of 5 the ribbon upon the article to be ornamented, and separating the deposited length of ribbon from the portion of the leaf remaining upon the supporting strip.

In depositing the metallic leaf it is customary to apply to the area of the book or other article purposed to receive the metallic leaf a sizing liquid, and next to downwardly press the metallic leaf upon the sized area by means of a pressure block. Heretofore the operating 10 face of the pressure block has been flat, therefore the leaf was not pressed uniformly upon the area to receive it, particularly when the receiving area did not happen to be perfectly flat, or when the receiving area was 15 curved. Furthermore the operator could seldom judge whether or not the flat operating surface of the block was in operating contact with all parts of the receiving area. For these reasons the adherence of the leaf 20 was often uncertain and imperfect.

The essential objects of my invention are to obviate the disadvantages above set forth; to insure a more perfect and uniform adherence of leaf to the object to be ornamented; to 25 effectively and efficiently dispose of the denuded supporting strip; to embody in the device for disposing of the supporting strip means for advancing the gold leaf over the face of the pressure block; to prevent over rotation of the take up roll or shaft; to afford a 30 means of predetermining the length of leaf intended for deposit upon the article to be ornamented; and to combine the above advantages in a structure of maximum strength 35 and lightness.

To the above ends primarily my invention consists in such parts and in such combinations of parts as fall within the scope of the appended claims.

45 In the accompanying drawings which form a part of this specification,

Figure 1 is a side elevation of a hand tool or machine embodying my invention,

Figures 2, 3 and 4, sections of the same on 50 lines 2—2, 3—3, and 4—4 respectively of Fig-

ure 1, the take up roll being omitted in Figure 3, and

Figure 5, a side elevation of the tool in tilted or severing position.

Like reference characters indicate like 55 parts throughout the views.

As herein illustrated my device includes a thin upright body 7 preferably of aluminum or other light metal, cast with a lateral extension 8 approximately midway the length 60 of its upper edge from which projects a vertical rib integral with the extension and body and extending to a pressure block 10 cast with the body and extending laterally from the lower edge or margin of the latter below the 65 extension, and extending longitudinally from the front end of the body to a point more than midway its length. In detail the block 10 comprises a transversely rectangular metallic body portion 12 having a downwardly 70 inclined forward end 13 continuous with a broad downwardly inclined and projecting severing lip 14, having a leaf dividing edge 15. Fixed by cement or otherwise to the lower face of the body portion 12 of the block, 75 which face is longitudinally convex, is a resilient pad portion 17 of rubber or other resilient material, whose forward end abuts against the lip 14, and whose lower face 18 is longitudinally convex or arcuate and forms 80 the bearing or operating face of the pressure block. Upon the exposed outer face of the portion 12 of the pressure block are a series of graduated lines 20 dividing the face into 85 inches and fraction of inches to form an index.

An upright handle 22 rests at its lower end upon the extension 8 and is held thereon by a screw 24 in the handle passing through a perforation 25 in the extension. A nut 26 on 90 the screw abuts against the lower face of the extension.

Fixed in a threaded opening 28 in the forward portion of the body 7 is the threaded end of a pin 30 loose in the central perforation 31 of a delivery package roll 32 upon whose periphery is wound in a coil 33 the usual supporting strip 34 of paper and a ribbon of metallic leaf 35 slightly adhering to the inner face of the strip. For tensioning 95 100

the roll 32 in pin 37, fast in the body 7 adjacent the pin 30, has a thread 39 upon which is a milled nut 41 provided with an annular recess 42 for the reception of a flat tension spring 44 provided in its rear portion with a hole 45 to loosely receive therethrough the reduced portion of the nut 41. The forward portion of the spring 44 is provided with a lateral rounded projection 47 adapted to register in the roll perforation 31. The pressure of the spring 44 retains the package or supply roll 32 against excessive rotation, and the movement of the nut 41 upon the pin 37 accommodates the spring to rolls of varying widths.

15 The body or frame is provided in its rear portion at a point above and behind the end of the block 10 with a hole 49 through which loosely passes the reduced portion 50 of a drawing and take up roll, indicated generally by 51, whose body portion 52, of greater diameter, forms a resultant end shoulder 53 which abuts against the front face of the body 7. The take up roll has its surface preferably milled or roughened to facilitate the adherence thereon of the end of the supporting strip 34 which adherence may be supplemented by applying glue to the surface of the roll. The roll portion 50 projects beyond the rear face of the body 7 and is provided with a screw thread 55. A peripheral-milled operating wheel 56 is provided with a central opening 57 having a thread 58 engaging the thread 55, and is fixed in any desired position upon the roll portion 50 by a lock nut 59 upon the latter. When thus locked the wheel 56, being rigid on the roll, may be manually turned to wind upon the roll portion 52 the backing strip 34. For the purpose of preventing backward rotation of the roll the following means is employed. A friction disk 61 of felt or the like is provided with a central opening 62 through which loosely passes the portion 51 of the roll. One face of this disk bears against the body 7. Adjacent this disk or fixed thereto is a backing or disk 64 of leather having a central opening 65 for the loose passage therethrough of the roll. The member 56 abuts against the disk 64, and by locking the former in different positions upon the roll the degree of frictional engagement of the disk 61 upon the body may be regulated.

55 In employing my device the roll 51 is manually turned, which draws a length of the backing strip 34 faced with the ribbon of metallic leaf 35 from the package roll 32 over the operating face 18 of the presser block the distance desired to cover the length desired to be ornamented, assisted by the index 20. In Figure 1 the metallic leaf or film is shown extending the entire length of the block. The operator next, with the handle 22 grasped in his hand, presses the rear end of the pressure

70 to be ornamented, and forwardly rocks the block until the forward corner of the block alone is depressed in the position shown in Figure 5. During this operation the length of metallic leaf has been smoothly deposited upon the object to be ornamented, and the final downward pressure of the leaf dividing edge 15 of the severing lip 14 disunite the deposited length of metallic film from the unused portion thereof.

75 It will be noted that the longitudinally convex form of the bottom surface of the pressure block 10 presents a rocking surface, and thereby produces a uniform and complete pressure of the metallic leaf length throughout its entire area, as is not possible were the bottom surface of the block flat. This is particularly apparent when the object to which the metallic film is applied is not perfectly flat or is curved.

80 The yielding character of the pad portion 17 of the pressure block is of assistance when interstices or pebbled surfaces are encountered in the object to be operated upon.

85 The drawing and take up roll 51 packages the exhausted portion of the backing strip; confines the course of travel of the strips to the face of the block, and affords a steady pull upon the delivery roll 32.

90 Since the tool should be preferably of light weight, and for that reason is in this instance made of cast aluminum, it will be noted that the web or rib 9 cooperating with the extension 8 and block 10 insures sufficient strength and rigidity to prevent fracture while the arrangement does not interfere with the operation of the parts nor with the travel of the strip.

95 I claim:

1. In a hand tool of the character described, 100 an upright body, a handle carried by the body, a pin in the body adapted to rotatably support a backing strip and a metallic ribbon, and a longitudinally convex pressure block upon the body below the pin adapted to slidably receive the backing strip.

105 2. In a hand tool of the character described, an upright body, a handle supported upon the top of the body, a pin in one end of the body adapted to rotatably support a coil of metallic ribbon and a backing strip therefor, a drawing roll rotatably mounted in the other end of the body adapted to retain an end of the backing strip, and a longitudinally convex pressure block upon the bottom of the body between the pin and roll in the path of the strip.

110 3. In a hand tool of the character described, 115 an upright body, a handle carried by the body, a pin in the body adapted to rotatably support a backing strip and a metallic ribbon, and a pressure block upon the body below the pin comprising an oblong body portion and a longitudinally convex resilient pad 120

portion upon the body portion over which the strip is adapted to pass.

4. In a hand tool of the character described, an upright body, a handle supported by the body, a pin in the body adapted to support a delivery package roll rotatably mounted upon the pin comprising a backing strip and a ribbon of metallic leaf coiled thereon, a roll rotatably mounted in the body and spaced from the pin adapted to draw and receive the backing strip, and a pressure block upon the body intermediate the rolls and in a plane below the rolls comprising an oblong metallic body portion, a downwardly inclined metallic severing lip upon the forward end of the body, and a longitudinally convex pad portion fixed to the bottom of the body portion and abutting against the lip in the path of the backing strip.
- 20 5. In a hand tool of the character described, a thin upright body, a lateral extension integral with the upper end of the body approximately midway its length, a longitudinally disposed laterally projecting convex pressure block integral with the lower portion of the body below the extension, a vertical rib integral with the body, the extension, and an intermediate portion of the block, an upright handle fixed to the extension, a laterally projecting pin fixed in the forward end of the body adapted to rotatably support a package delivery roll, a drawing roll rotatably mounted in the body above and in the rear of the block parallel with the pin, and an operating wheel upon the roll.

In testimony whereof I have affixed my signature.

GEORGE E. LITTLEFIELD.
